UNITED STATES PATENT OFFICE.

WILLIAM PARKER HAMMOND, OF BOSTON, MASSACHUSETTS, ASSIGNOR TO UNITED SHOE MACHINERY COMPANY, OF PATERSON, NEW JERSEY, A CORPORATION OF NEW JERSEY.

SHOE-RACK.

1,232,298.

Specification of Letters Patent.

Patented July 3, 1917.

Application filed May 1, 1914. Serial No. 835,728.

To all whom it may concern:

Be it known that I, WILLIAM P. HAMMOND, a citizen of the United States, residing at Boston, in the county of Suffolk and 5 State of Massachusetts, have invented certain Improvements in Shoe-Racks, of which the following description, in connection with the accompanying drawings, is a specification, like reference characters on the 10 drawings indicating like parts in the several figures.

This invention relates to racks of the type commonly used in shoe factories for receiving and conveying the shoes from one part 15 of the factory to another.

The invention has among its objects to reduce the damage caused to the shoes by placing them in, or removing them from, the racks, and the damage caused while the 20 shoes are being transferred in the racks from one part of the factory to another; and to devise a rack that will be particularly substantial and durable and will be capable of a wider range of use than the racks now 25 employed. The particular manner in which it is proposed to accomplish these objects, and the various features of the invention, will be readily understood from the following description, reference being made to the 30 accompanying drawings, in which,

Figure 1 is a side elevation of a rack constructed in accordance with this invention; Fig. 2 is an end elevation of the rack;

Fig. 3 is a perspective showing certain 35 details of the shelf construction;

Fig. 4 is a perspective of a detail of construction; and

Fig. 5 is a sectional view showing a novel 40 form of covering for the shelves.

The rack shown comprises a base frame 45 consisting of two sills 2 of angle iron connected by cross bars 3 and two end frames removably secured by means of bolts to opposite ends of the base frame. Each of 50 these end frames consists of two corner standards 4 of angle iron connected at their upper ends by a cross tube 5 and near their lower ends by cross braces 6. Two end straps 7 (see Fig. 2) also are included in 55 each end frame and are secured at their lower ends to the cross braces 6, their upper ends extending into slots formed in the lower side of the cross tube 5. Diagonal braces 8 connect each of the end frames to the base frame, as best shown in Fig. 1, and

a tie rod 9, extending longitudinally of the rack, through the cross tubes 5 serves also to brace the rack. This tie rod is provided with adjustable nuts by which the ends of the rack can be sprung toward each other. 60 This construction of frame is substantially like that described in my Patent No. 1,100,072, June 16, 1914. When the bolts, by which the end frames are secured to the base frame, are removed, and the tie rod 9 is removed, 65 the end frames may be folded down on to the base frame as described in said application.

These end frames constitute the supports for a series of single shelves arranged in 70 staggered relationship, as shown in Fig. 2, the shelves being supported at their opposite ends by means of brackets 10 secured to the corner standards 4 and by screws or bolts 11 extending through one or both of the end 75 straps 7 into each end member of the shelf.

The shelves are of novel construction and are designed particularly with the purpose of eliminating tacks, nails, or screws, which are liable to work loose during the use of 80 the rack, thus weakening the shelves; and of avoiding rack damage to shoes caused by striking them against fastenings that have worked into a protruding position. In the construction shown, each shelf is of rectangular form and comprises two side members 12 and two end members which may be fastened to the side members by nails or screws driven through the end members into the side members longitudinally thereof. The 85 heads of these nails or screws are covered either by one flange of the standard 4 or by one of the end straps 7 so that there is no possibility of these fastenings working loose and causing the trouble above mentioned. No other screws or nails are used in the shelf. The side members are connected by one or more bridge pieces 13, 90 three such pieces being shown in the present construction although the number obviously will vary with the requirements of each particular case. Each bridge piece, as best shown in Fig. 3, extends across the rack with its ends abutting against the inner faces of the side members 12, the opposite 95 ends of the bridge piece being provided with tongues set into suitable slots formed in the side members to prevent any displacement of the bridge piece relatively to the side members. A tie rod 15 extends transversely 100

105 of the bridge piece. The side members 12 are provided with a series of slots 16, 110 which are adapted to receive the tongues of the bridge piece. The side members 12 are provided with a series of slots 16, 110 which are adapted to receive the tongues of the bridge piece. The side members 12 are provided with a series of slots 16, 110 which are adapted to receive the tongues of the bridge piece.

through the side members 12 and lies close beside the bridge piece 13, this member preferably being grooved, as indicated in Fig. 5, to receive the tie rod and the ends of the tie rod are threaded to receive nuts by which the side pieces 12 can be drawn firmly against the ends of the bridge piece 13.

The bottom of the shelf consists of several rods or dowels 16 extending longitudinally of the rack and having their ends supported in the end pieces of the shelf and in the bridge pieces 13, each member 13 being bored just above the tie rod 15 to receive the dowels 16, as shown in Figs. 3 and 5. Each shelf also includes a number of transverse partitions 18 extending across the shelf parallel to the bridge piece 13 above the dowels 16 and dividing the shelf into a series of compartments. These partitions may be merely thin strips of wood, having their ends set into slots formed in the opposite side members 12. They need not be fastened to the side members since the tie rods 15 will prevent the side members from being sprung apart far enough to permit the removal of the partitions. Preferably the heads or nuts of the tie rods 15 are countersunk in the side members 12 so that any danger of striking the shoe against one of these parts is avoided.

The entire shelf, with the exception of the tie rod, preferably is made of wood and in order to reduce the fire risk attending the use of these racks, the shelves preferably are treated with some fireproofing compound. A convenient method of treating the shelves consists in immersing them in a hot solution of boracic acid for a length of time sufficient to allow the acid to penetrate into the wood. This treatment materially reduces the combustibility of the wood, and inasmuch as the frame of the rack is made of metal, the fire risk attending the use of a rack constructed in this manner is substantially less than that incident to the use of the ordinary wooden racks.

The rack is provided with casters 20 secured to the bottoms of the sills 2 by means of bolts 22. There is great liability, if the casters are secured directly to the sill members, of breaking the casters due to the shock produced by the caster striking some obstruction, the entire momentum of the rack loaded with shoes being transmitted to the caster through an unyielding connection. In order to avoid this difficulty a member of yielding material, such for instance as leather or felt, is interposed between the sill members and each caster 20, as indicated at 22' in Figs. 2 and 4. This member very materially reduces the breakage of casters produced in the manner just described and, consequently, reduces the annoyance and expense caused by such breakage.

In moving shoe racks about a factory they

are very likely to strike each other and to interlock with each other where some part of one rack catches on a bolt head or other projection extending from the side of another rack. In order to avoid this difficulty the rack shown is provided at each of its base corners with a bumper 24 which is secured to the sill 2 by a bolt 26. This bumper is shaped to fit around the corner of the frame of the rack and has an edge face projecting laterally beyond the ends of any of the projections at the side of the rack. This face is curved convexly from end to end, as shown in Fig. 4, and the forward end of the bumper projects beyond the end of the rack, so the edge face of this part of the bumper swinging inwardly toward the rack, as clearly shown in Fig. 4. The opposite edge of the bumper may be curved forward to produce a point at the forward end of the bumper and its upper face preferably is sloped downwardly toward this point so that, if the bumper of one rack rides up on the bumper of another, it will tend to slide off again and free the racks from each other. In the case of a collision between the rack and another rack, post or other obstruction, the bumper will usually strike the obstruction on its outer curved edge so that it will swing the rack away from the obstruction.

After a shoe rack has been in use a short time it usually becomes so dirty that it is unfit for use in the finishing room even if it were in other respects suited to such use. It has been customary to use a different set of racks in the finishing room, partly for the reason just mentioned and partly because, if the shoes were supported in a shelf rack after their bottoms had been finished, the bottoms would be marred and the shoes would be likely to strike each other or the edges of the shelves and injure the finished edges of the shoes. The present invention, however, provides a removable cover of novel construction with the aid of which a rack used for the making room operations can also be used in the finishing room. This cover comprises a double thickness of cloth 28, preferably fleece lined with the fleece side outward. This may be, and preferably is, merely a strip of cloth folded over. The strip is stitched transversely to form therein a series of pockets of substantially the dimensions of the compartments between the adjacent partitions 18 of the shelf. A stiffening member 30, which may consist of a piece of fiber board, is inserted in each of these pockets and is of such dimensions that, when the cover is placed in its operative position on the shelf, this stiffening member will hold the cover smoothly in the bottom of the compartment in the shelf. The pockets are formed in such relationship to each other that, when the stiffening members are in them and they are in their

proper positions in the compartments of the shelf, the material of the cover between adjacent pockets will fold smoothly over the partitions 18. This cover, therefore, protects the bottoms and edges of the shoes from abrasion or soiling by contact with the rack while the construction of the shelves keeps the shoes out of contact with each other. Either side of the cover may 10 be used and when it becomes soiled it may be laundered after first removing the stiffeners 30. If desired the cover may be shaped to cover the inner faces of the side members 12 at the ends of each compartment in the 15 shelf so that the heel and toe ends of the shoe will be prevented from striking these side members. Usually, however, this precaution is unnecessary.

I have claimed the novel bumper disclosed 20 herein in my divisional application Serial No. 37,455, filed July 1, 1915, and it is therefore not claimed in this application.

Having thus described my invention, what I claim as new and desire to secure 25 by Letters Patent of the United States is:

1. In a shoe rack, the combination with a supporting frame and one or more shelves supported in said frame, each shelf having a plurality of independent shoe receiving 30 compartments, of a removable cloth cover for each shelf, said cover having a series of pockets formed therein, and stiffening members positioned, respectively, in the pockets of the cover, said members being shaped to 35 fit in the compartments of said shelf and hold the cover in proper position thereon.

2. In a shoe rack, the combination with a frame and one or more shelves supported in

said frame, each shelf having a series of transverse partitions forming a plurality of 40 independent shoe receiving compartments in the shelf, of a removable cloth cover for each shelf, said cover consisting of a double thickness of cloth stitched transversely to form therein pockets of substantially the 45 dimensions of the compartments in the shelf, and a stiffening member in each of said pockets, said pockets being constructed and spaced from each other in such a manner as to lie flat in the compartments of the 50 shelf while enabling the material between adjacent pockets of the cover to fold over the partition between adjacent compartments in the shelf.

3. In a shoe rack, the combination with 55 a frame and one or more shelves supported in said frame, each shelf having a series of transverse partitions forming a plurality of independent shoe receiving compartments in the shelf, of a removable cover of flexible material for each shelf having pockets corresponding to said compartments and a stiffening member for each of said compartments, said member being constructed to hold said cover in the bottom of the 60 pocket while allowing the material of the cover between adjacent compartments to 65 fold over the partitions separating the compartments.

In testimony whereof I have signed my 70 name to this specification in the presence of two subscribing witnesses.

WILLIAM PARKER HAMMOND.

Copies of this patent may be obtained for five cents each, by addressing the "Commissioner of Patents,
Washington, D. C."

It is hereby certified that in Letters Patent No. 1,232,298, granted July 3, 1917, upon the application of William Parker Hammond, of Boston, Massachusetts, for an improvement in "Shoe-Racks," errors appear in the printed specification requiring correction as follows: Page 3, lines 63-64, claim 3, for the word "compartments" read *pockets*; same page and claim, line 66, for the word "pocket" read *compartment*; and that the said Letters Patent should be read with these corrections therein that the same may conform to the record of the case in the Patent Office.

Signed and sealed this 27th day of August, A. D., 1918.

[SEAL.]

F. W. H. CLAY,

Acting Commissioner of Patents.
